UNITED STATES PATENT OFFICE.

PETER J. PAULY, JR., AND GUY TANNER, OF ST. LOUIS, MISSOURI.

FLUSH-VALVE.

1,157,035.

Specification of Letters Patent.

Patented Oct. 19, 1915.

Application filed April 12, 1915. Serial No. 20,903.

To all whom it may concern:

Be it known that we, PETER J. PAULY, Jr., and GUY TANNER, citizens of the United States, residing at St. Louis, State of Missouri, have invented certain new and useful Improvements in Flush-Valves, of which the following is a full, clear, and exact description, reference being had to the accompanying drawings, forming a part hereof.

Our invention has relation to improvements in flush-valves for closets; and it consists in the novel features of construction more fully set forth in the specification and pointed out in the claims.

The present improvement is particularly directed to flush-valves for closets of jails, the object being to provide a valve which may not be tampered with and put out of order by the prisoner; one which may be readily installed in a jail cell; one which can be adjusted to deliver any predetermined quantity of flush water; one susceptible of easy manipulation and responsive to a minimum amount of exertion or pressure; one which may be installed in any position relatively to the bowl which is to be flushed; and one possessing further and other advantages better apparent from a detailed description thereof in connection with the accompanying drawings, in which—

Figure 1 is a side elevation of a bowl showing the application of our invention thereto; Fig. 2 is a top plan of the valve with parts broken away, showing in section the cell wall to which the same is attached, and a portion of the piping coupled to the valve; Fig. 3 is a cross-section on the line 3—3 of Fig. 2; Figs. 4, 5, and 6 are longitudinal middle sections of the valve casing showing the closed, partially open, and full open positions of the valve respectively; Fig. 7 is a face view of the main or inner valve; and Fig. 8 is a face view of the terminal or auxiliary valve and its gasket, a portion of the latter being broken away.

Referring to the drawings, B represents a conventional closet bowl from which leads the usual soil pipe S, the flush water being delivered by the riser or supply pipe P coupled to the valve-casing C in any manner known to the art. In the present example, the valve-casing is coupled to the wall w of the jail cell in a manner to be more particularly hereinafter described, the bowl being connected up to the valve-casing by suitable piping E, E', the last mentioned

pipe being connected or screwed to the discharge nipple or leg 1 of the valve-casing. The connections are effected by the use of the usual unions or equivalent devices conventionally shown herein, well known in the art, and requiring no detailed description.

The valve-casing C, in the present embodiment of our invention, is composed of a number of individual parts, each of which subserves a special function, the details of the valve-casing and of the valve operating therein being as follows: The valve casing comprises a hollow member terminating at one end in a chamber or "cylinder" 2, and at the opposite end in a chamber 3, the cylinder being closed at its outer end by a screw-cap 4. Leading from the chamber 3 is the discharge leg or nipple 1 above referred to. Both chambers 2, 3, communicate with the intake leg 5 or that which is coupled to the supply pipe P, the communication between said leg 5 and the chamber 2 being permanent, and that between said leg and the chamber 3 being periodic or intermittent, depending on the position of the main valve as more fully hereinafter described. The axes of the chambers 2, 3, are coincident, the said chambers being traversed by a valve-stem 6 which operates

through a stuffing-box at the end of the valve-casing beyond the chamber 3, the gland or follower a of said stuffing box terminating in a head 7 provided with radially disposed sockets b, for the insertion of a steel pin, nail, or equivalent device whereby the said member a may be turned or rotated for a purpose presently to appear. The outer terminal of the valve stem is provided with a reduced screw-threaded extension 6' over which is passed a flanged nut 8 adapted to shoulder against the stem at the base of the extension 6', there being interposed between the gland a and the nut 8, an expansion spring 9 coiled about the valve-stem, the tendency of the spring being to force the valve-stem outwardly. The gland a is virtually a hollow nut traversed by the valve-stem, said nut screwing into the end of the valve-casing as shown, and while fulfilling its function as a gland, it at the same time serves as a means of adjusting the tension of the controlling spring 9, it being obvious that a turn of the member a in one direction will compress the spring so as to increase the tension thereof, and a turn in the opposite direction will relieve the spring

110

so as to reduce the tension thereof, the packing ring a' of the stuffing box being made of rubber, leather or other compressible material to allow for the turning of the gland 5 a in either direction, and yet maintain a tight joint through the stuffing-box.

The end of the valve-casing through which the valve-stem operates, terminates in a head h provided with a reduced screw-threaded nipple m which receives the shell or coupling 10, the latter abutting or shoudering against the head when driven fully home over the nipple (Fig. 2), the said shell having peripheral openings O through 10 which access may readily be had to the nut or gland a for manipulating the same as previously pointed out. The end of the shell or union 10 opposite that which couples to the head h of the valve-casing, is exteriorly 15 screw-threaded, the said threaded portion having mounted thereon an inner clamping nut 11, and an outer flanged ring or disk 12, the body of the ring being received by a circular opening in the cell wall w , the flange t 20 of the ring bearing against the face of the wall around said opening (Fig. 2). By this arrangement, when the nut 11 is driven against the inner face of the wall w , the outer face being engaged by the flange t of the disk or ring 12, the said wall is firmly 25 gripped between the members 11 and 12 and the valve-casing is rigidly secured to said wall. The ring 12 has a central opening of slightly smaller diameter than the cross-sectional diameter of the passage way of the 30 tubular shell or coupling 10, said opening receiving a cap-piece or cup 13 terminating at its edge in a flange or rim 14 which, while free to pass into the shell 10 is not free to 35 pass through the opening of the ring 12. In practice the ring 12 is first passed over the cap 13 after which the flanged or enlarged end of the cap is inserted into the shell 10, the terminal wall or closed end of the cap 40 being provided with a screw-threaded socket for receiving the reduced screw-threaded end 6' of the valve-stem. By giving the cap a few turns or rotations in proper direction the same will attach itself to the valve-stem 45 extension 6', the ring 12 being free to turn about the shell until arrested by the end of the shell engaging the shoulder s formed around the opening receiving the cap 13 (Fig. 2), the inner face of the ring being 50 by that time substantially flush with the inner face of the wall w against which the nut 11 is driven, thus causing the wall to be gripped between the members 11, 12, as previously described. The valve-casing being 55 thus secured not only to the wall w , but to the pipes P and E' , and being in the rear of the wall of the cell occupied by the prisoner (Fig. 1), it follows that tampering with the valve is practically impossible. Especially is this true in view of the fact that 60

the ring 12 which is within the cell, is finished off smooth, thereby preventing the prisoner from securing a firm purchase or grip thereon with any attempt to unscrew the same for purpose of removing the cap 70 13. If, after the assembling of the parts, the prisoner unscrewed the cap 13 from the reduced terminal 6' of the valve-stem, the cap could not be wholly removed because with any attempt to withdraw the same, it would 75 be arrested by the flange 14 fouling the shoulder s (Fig. 2).

The valve-stem 6 is provided with an inner reduced section or portion 6'' forming a shoulder r with the main section of the 80 valve-stem, said reduced section carrying the main valve V controlling the flow of the liquid from the intake 5 to the discharge spout 1, said valve comprising a body portion terminating at the end facing the screw-cap 4, 85 in a flange e , the opposite end of the valve being provided with a gasket 15 held in place by a screw ring or nut 16 passed over the valve, the gasket resting for the closed position of the valve on an annular seat or 90 shoulder h' , at the inner terminal of the chamber 3, between the points of intake and discharge. Along the inner circle of the flange e is formed an annular bead, rib, or ridge u serving as a seat for the auxiliary or 95 starting valve V' to be presently described in detail. The valve V has a free movement longitudinally along the stem section 6'', between the valve V' and the shoulder r , and when seated, it is held against its seat 100 h' by the combined pressure of the water behind it and by the pressure due to the tension of the spring 9 which draws the valve V' against the seat u thereof (Fig. 4). Within 105 the circle of the seat u , the valve V is provided with a series of circularly disposed ports or passage-ways i , which are cut off from the intake 5 when the valve V' is seated against the seat u , so that no water can 110 flow into the chamber 3 or nozzle 1.

The section 6'' of the valve-stem terminates in a reduced screw-threaded extension 6''' to which the valve V' is screwed, and when fully driven home, the valve shoulders against the unthreaded portion of said extension (Fig. 6), a suitable gasket 17 and washer 18 forming the inner terminal of the valve, the gasket 17 directly engaging the seat u of the main valve V . At an intermediate point of the valve V' is formed an 115 annular flange or rib 19 exterior to which is a screw-threaded terminal reduced portion receiving a cup-shaped packing ring 20 which overhangs the flange 19, said packing ring being held in place by the flange 21 of a cup-shaped screw-cap 22 passed over the screw-threaded terminal of the valve, the peripheral walls and bottom of the screw-cap extending some distance beyond the screw-threaded terminal of the valve, there- 120 125 130

by forming a chamber *d* in which is free to play the head 23 of a perforated check or retarding valve whose hollow stem 23' is free to traverse loosely an opening *c* in the bottom of the cap 22, the pocket *p* in the screw-cap 4 closing the rear end of the valve-casing C, affording ample freedom to the stem 23' for any movements to which it may be subjected. The face or end of the screw threaded terminal of the valve V' is provided with a series of radial grooves *m'* forming passage-ways or ports with the head 23 of the perforated check or retarder valve 23, 23', when the head thereof is in engagement with the valve V' (Fig. 5) through which ports water is free to flow inwardly into the open end of a chamber 24 of the valve, the opposite or inner end of said chamber in turn communicating with the cylinder or chamber 2 of the valve-casing C through a series of radially disposed ports or passages *n* formed in the valve body and opening at their outer ends on the peripheral walls of the valve and within or behind the overhanging portion of the packing ring 20. For convenience the passage of the retarding valve 23, 23', is designated by the reference letter *c'*.

It will be seen from the foregoing that all the valves (V, V', 23, 23'), are ported, that is to say, they are provided with passage-ways or ports subserving certain functions and which contribute to the easy working of the device. The auxiliary or starting valve V' is in effect a piston valve, operating as it does in the cylinder 2, the main valve V being a reciprocating valve loose on the stem section 6", and lagging behind the valve V' by reason of the play or independent movement accorded it between the shoulder *r* and the gasket 17 of the valve V'.

The operation of the valve may be described as follows: When the device is not operating, the spring 9 draws the stem 6 outwardly causing the starting valve V' to bear against the main discharge valve V, the latter seating against the shoulder *r*, not only in response to the tension of the spring, but by reason of the pressure against it from the water in the riser P, and cylinder 2, it being obvious that the chamber of the cylinder will be permanently flooded or filled with water, the latter circulating freely through the passage-ways *n*, chamber 24, passage-ways *m'*, cap 22 and passage *c*, the cap 22 being in effect a part of the starting valve V'. The valve V' being thus surrounded by water is subjected to equal hydrostatic pressure on opposite sides and hence perfectly balanced, so that to dislodge this valve from its position of rest only the tension of the spring 9 need be overcome in starting the operation of flushing. When both valves V, V', are seated (Figs. 1, 4,) the water is cut off from the nozzle 1 and

hence from the bowl B. When (Fig. 5) the cap 13 is pushed inwardly so as to force the stem 6 inwardly a distance sufficient to bring the shoulder *r* (Fig. 4) of the valve stem up to the main valve V, the valve V' will have been unseated sufficiently to clear the seat or rib *u*, thereby exposing the ports *i* of the main valve to the water in the chamber 2 and that flowing in through the intake 5, the water now flowing into the chamber 3 and into the discharge nipple 1, the flow of the water through the valve V in a great measure removing the water pressure by which it was held against its seat when the ports *i* were closed by the valve V'. With this partial movement of the stem 6, and hence of the valve V', the ported check or retarding valve is unseated, the water in the chamber 2 confined between the cap 22 and the screw-cap 4, flowing freely through the cap 22, passages *m'*, chamber 24, and out through the passages *n* into the portion of the cylinder opposite the intake 5, as clearly shown by the arrows in Fig. 5. When the cap 13 and its stem 6 are pushed in their full limit (Fig. 6) the full force of the stream passes directly from the intake 5 to the discharge 1 through the chamber 3, and the flushing of the bowl continues until the valves again are closed or brought to the position indicated in Fig. 4. To unseat the valve V after the initial unseating of the valve V' can be accomplished with little effort, due to the fact that once the water finds its way through the ports *i*, the water pressures against the valve become practically equalized, and only the tension of the spring 9 need be overcome, the same as with the unseating of the starting valve V'.

The rapidity with which the parts resume their normal position after being moved to the position indicated in Fig. 6, depends of course on the tension of the spring 9 which tends to draw the stem 6 and its valves back to said normal position; but this rapidity is regulated by the cross-section of the port in the retarding valve 23, 23'. It will be seen by an inspection of Fig. 5, that with a return of the stem and valves to normal position, the check valve head 23 will seat over the port *c* of the cap 22, so that the only way the water can flow back into the rear end of the cylinder 2 (where a vacuum naturally forms) is through the port *c'*; and this port may be constricted in practice to allow the water to flow therethrough at any predetermined rate of speed, such speed depending on the time it is desirable to keep the valves unseated to flush the bowl thoroughly. Some bowls may require say four gallons of water for a thorough flush; others six gallons; and others eight gallons or some other quantity. And when a flush-valve is initially installed,

a retarding check 23, 23', with a cross-section of port conformable to the desired speed of return of the parts to normal position, is deposited in the cup 22. Should it be desired at any subsequent time to change the volume of flush water, the original check may be removed, and another check with a different size cross-section of port may be substituted. In Fig. 6 the arrows show the circulation of the water through the valves V' and 23, 23', the stem being supposed to be returning to normal or original position under the expanding action of the controlling spring 9. When the stem is driven inward its full limit the same is arrested by the cap 22 striking the screw cap 4 of the valve-casing C.

It is of course obvious that the details of the valve as shown might be materially departed from without in any wise affecting the nature or spirit of the invention. Neither need the valve be restricted in its application to flushing purposes, the title "flush valve" in no way restricting the scope of the invention or claims thereof. The member 13 operates as a push button or knob, playing freely in the shell 10, and in no wise interfering with the action of the spring 9; and whenever a bowl needs flushing all that the user of the bowl need do, is to push in the cap 13 as far as it will go (Fig. 6) when the apparatus will automatically release the water from the pipe P and flush the bowl, after which the parts will return to their original positions (Figs. 2, 4,) under the action of the spring 9, the length of time of such action depending on the size of the port opening of the retarding valve 23, 23', or its equivalent.

Having described our invention what we claim is:

1. A flush-valve provided with a casing chambered for the passage of liquid and having intake and discharge means communicating with said chamber, a valve-seat in the casing interposed between the points of intake and discharge, a ported main valve normally engaging said seat, a ported balanced starting valve seating against the main valve opposite the intake, the valves operating in the chamber of the casing, a spring-controlled operating stem fixed to the starting valve and passing loosely through the main valve, the latter having a limited movement along the stem to and from the starting valve, a limited movement of the stem in a given direction separating the valves and establishing communication between the intake and discharge through the ports of the main valve, means on the stem for unseating the main valve with a further movement of the stem in the same direction, thereby establishing direct com-

munication between the intake and discharge through the casing chamber, a member carried by the starting valve provided with a chamber in free communication with the ports of the valve and with an opening through which the liquid in the chamber of the valve-casing traversing the valve may freely circulate, and a ported check or retarding valve provided with a hollow stem loosely operating through said opening and terminating in a head in the chamber of the member aforesaid. 75

2. In a flushing apparatus of the character described, a starting valve comprising a member having a chamber opening through one end of the valve, a series of radial grooves on the end of the valve leading to the chamber, radial ports leading through the valve body from the interior of the chamber, a chambered cap carried by the valve and having its bottom spaced from the grooved end of the valve, said bottom being provided with an opening, a perforated disk valve in the chamber of the cap coöperating with the grooved end of the starting valve, and a ported stem forming a part of the disk valve and operating freely in and through the opening of the cap bottom. 80 85 90

3. In a flushing apparatus of the character described, a valve-casing, a valve-supporting and operating reciprocating stem passed through one end of the casing, a stuffing box comprising a packing ring and screw gland traversed by said stem, the outer end of the stem being provided with a reduced screw-threaded extension, a nut passed over the same and shouldered against the stem, a protecting cap screwed over the screw-threaded extension and terminating at its inner end in a flange, a ring passed over the cap and provided with a shoulder adapted to foul the flange on the cap with an attempted removal of said cap, a shell screwed to the ring and valve casing and provided with openings to afford access to the screw gland, an expansion spring coiled about the stem and interposed between the gland and nut on the stem, and a clamping nut on the screw-threaded portion of the shell operating in conjunction with the ring to grip a suitable wall or fixed support between them, the said support being provided with an opening for the insertion of the shell. 105 110 115

In testimony whereof we affix our signatures in presence of two witnesses.
